UNITED STATES PATENT OFFICE.

PAUL ARTHUR HIRSCH, OF NEW YORK, N. Y., ASSIGNOR TO FURNACE ENGINEERING COMPANY, INC., OF NEW YORK, N. Y., A CORPORATION OF NEW YORK.

PULVERIZING MACHINE.

Application filed November 20, 1924. Serial No. 751,119.

This invention is a pulverizing machine, having reference particularly to the pulverizing of coal, or other fuels or materials, to an extreme degree of reduction. The invention is herein shown embodied in a type of pulverizing machine having a chambered casing, with an operating shaft therein, and impact beaters or paddles revolved by the shaft, while axial air flow causes progressive 10 advance of the material being reduced; although features of the present invention may be otherwise embodied. The illustrated design of pulverizing machine is adaptable for very fine reduction of coal, for example, for 15 direct feed to the fire or furnace in suspension in air. A prior pulverizer of the type and for the purpose referred to, is illustrated in my Patent No. 1,479,540 of January 1, 1924; the present invention being in 20 some aspects an improvement on said prior patent and being in other aspects directed to independently useful features of invention.

One of the main objects of the present invention is to permit substantial increase of 25 speed, as compared with speeds heretofore possible, giving maximum output or capacity with minimum floor space, and superior pulverization. Fairly rapid speeds have already been attained in pulverizers of this 30 class, but the matter of securing extreme speeds raises distinct problems in respect to operativeness, efficiency, consumption of power etc. which have not heretofore been overcome until solved by the present invention. The machine herein described affords 35 a very fine and uniform degree of pulverization. It gives large capacity with relative low power consumption. At the same time wear is minimized and the life of the machine prolonged. Its small size and floor 40 space make it available in places with restricted available space. Other and further objects and advantages of the present invention will be explained in the hereinafter following description of an illustrative embodiment thereof, or will be apparent to those skilled in the art. To the attainment of the 45 objects and advantages referred to the present invention consists in the novel method and machine, and the novel features of operation, combination, arrangement and construction herein illustrated or described.

In the accompanying drawings Fig. 1 is 50 a side elevation of a pulverizing machine

illustrating the present invention, the same 55 partly broken away to show the interior parts in section.

Fig. 2 is a right hand elevation partly in section on the line 2—2 of Fig. 1.

Fig. 3 is a right hand elevation partly in 60 section on the line 3—3 of Fig. 1.

Fig. 4 is a view corresponding with a part of Fig. 2 showing a modified construction.

Fig. 5 is a right hand elevation, partly in 65 transverse section, of a modified construction.

Fig. 6 is an elevation and section similar to part of Fig. 5 showing a further modified structure.

Fig. 7 is a view similar to Fig. 1 showing 70 a modified form of machine.

Fig. 8 is a right hand elevation partly in section on the line 8—8 of Fig. 7.

Fig. 9 is a view similar to Fig. 7 showing 75 the same general type of machine, with modifications.

Fig. 10 is a partial view similar to Fig. 7, with certain modifications.

Referring in detail to the illustrated structure, Fig. 1 shows a pulverizing machine of a horizontal type, although it could as well be vertical as in my Patent 1,479,541. Mounted on a base piece 11 is shown a cylindrical drum or casing 12, preferably fixed 80 against rotation. The drum may be constructed in halves, the top half connected to the lower half by a hinge 13 and permanently secured in place by bolts. The lower right hand part of the casing is shown as 85 having a dropped extension 14 in which certain foreign matter may be collected as will be described, a tube or receptacle 15 being attached to the extension, and having a removable cover 16 by which the foreign matter may be removed from time to time. The drum or casing, encloses a chamber or chambers and is shown as lined with a steel cylinder 17, which lining is perforated with a hole 18 above the extension 14, to permit 90 heavy matter to be discharged.

The drum at its right end is closed by a circular end wall or casting or head 19 having a central or axial opening 20 by which the material to be pulverized can enter the chamber within the drum. The head 19 is shown formed with an extension 21 containing a receptacle or passage 22 for the re-

ception and discharge of foreign matter, such as bits of iron, accompanying the entering fuel. The passage 22 is open and freely discharges the foreign matter, and at the same time admits air to the drum, which however may be regulated by a door or damper over the exit of the passage.

The extension 21 of the head 19 is shown as giving support to one of the bearings 24 of the operating shaft 25, the other end of the shaft having a similar bearing 26 supported on a fixed part as will be described. The shaft is shown as provided with a cone pulley 27 at its right end by which it drives certain devices to be referred to, and at its left end the shaft has an extension 28 by which it may be driven in any manner, through belt and pulley, direct coupled motor, turbine or the like.

The left or discharge end of the drum is shown as closed by an end wall or head 29 having a central or axial opening 30 through which the pulverized materials and air may pass from the drum. Preferably the pulverizing is done inside the drum, while the draft for the progressive advance of the air and materials is provided by a suction fan or blower located beyond the drum. For this purpose a fan casing 31 is shown, which may be partly integral with the head 29. The fan casing has a lateral extension 33 upon which the shaft bearing 26 is mounted as before stated. The fan casing has also a peripheral extension 34 formed with a tangential passage or exit opening 35 by which the materials are blown out of the apparatus. The exit extension 34 is flanged and may be coupled with suitable pipes for conducting the air and pulverized material to a furnace or elsewhere.

The infeed of the fuel may be by a hopper 37. This may be formed as a separate casting, mounted upon the head 19 and its extension 21. The hopper is seen in sectional elevation in Fig. 3. It may have an upper deflector or inclined flange 38 preventing heavy matters, such as scraps of iron, from passing directly into the pulverizing chambers. The hopper casting is also formed with a curved flange or apron 39 extending over the shaft and downwardly at the two sides so as to protect the shaft, and to cause the discharge of heavy matters into the passage 22 beneath. An upward lip or flange 40 on the apron 39 assists the exclusion of heavy pieces from the interior.

Any type of regulable infeeding device may be employed, to be located at 42, and this may be driven, through reduction gearing, by a pulley 43 and belt 44. The pulley 43 may be a cone pulley cooperating with the cone pulley 27, and the belt 44 may be adjustable on said pulleys by a belt shifter 45 sliding along a bracket 46 and controlled by an adjusting wheel 47 so as to regulate the

rate of feed of coal or other material to the pulverizer.

There may be a single pulverizer chamber within the drum, or a series of them, and Fig. 1 shows a first reduction chamber 51 and a second reduction chamber 52, within which the fuel will be progressively pulverized by the fast rotating beating means mounted within each chamber upon the shaft 25. Thus the shaft is shown as having pinned or keyed to it in each chamber a hub 54 on which is mounted a disk 55, around the circumference of which are mounted a series of peripheral beaters or paddles 56. Such a beater structure has been already explained in said prior patent and needs no further detailed description.

Located between the first and second pulverizing chambers 51 and 52 is shown a means for effecting a sudden obstructing of the whirling motion produced by the fast rotating paddles in chamber 51. This whirl obstructer may be in the form of a series of blade-like vanes 60 set edgewise to the axial advance of the material and extending from or near the periphery of the chambers to or toward the shaft. Preferably the vanes 60 are relatively stationary, and they may stand radially or otherwise. The action of such vanes has been described in said prior patent. The several vanes may be mounted and interconnected by means of a peripheral ring 61 attached to the lining 17, and an inner ring 62 loosely surrounding the shaft 25.

Beyond the second pulverizing chamber 52 and between it and the fan casing is shown another set of obstructing vanes 65, with an outer ring 66 interconnecting them. These have a special function herein, in addition to the function possessed by the vanes 60; this to be explained more fully hereinafter.

It will be noticed that within and between the pulverizing chambers there are no annular or other division walls or so-called diaphragms, nor any substantial obstruction to the axial progress of the materials, between the axial entrance aperture 20 in the head 19 and the axial exit aperture 30 in the head 29. This aperture 30 is of considerably less diameter than the pulverizing chambers, and of less diameter even than that of the pulverizing elements, that is, the diameter from tip to tip of the paddles. In these and other respects to be explained the present invention is materially different from said prior patent and other prior structures of which I am familiar. The aperture 30, indeed, is shown of such small diameter that materials progressing through it pass into the interior of the rotary fan structure, an important consideration.

The fan chamber 32 may be of varying diameters, being shown of substantially the diameter of the main casing or drum, but

the fan 70 is shown of considerably smaller diameter, for reasons to be more fully described. The fan 70 is mounted on a hub 71 keyed to the shaft 25, or to the reduced extension 28 thereof, and in the form shown comprises spokes 72, of which there may be two series, their outer ends supporting annular plates 73 which directly carry the fan blades 74. An important feature is that the fan blades are preferably not radial as in prior structure, but have their outer extremities slanted backwardly from the direction of rotation. The tilt is shown in Fig. 2 as approximately 60° from the radius, although it might be greater or less. The tilt of the fan blades should preferably be between 25° and 75°, but these limits give inferior action, and in practise I have found the best tilt to be about or between 45° and 60° from the radius. The fan blades are shown in Fig. 2 as comprising two series of short flat plates extending between three of the annular reinforcing rings 73, the whole rigidly secured together and forming a durable fan capable of withstanding the strains resulting from the high centrifugal force.

The fan blades 74 instead of being flat as in Fig. 2 may be advantageously constructed with a camber or curved form as indicated at 75 in Fig. 4. In this case the angle or lead of the blades should be measured as the angle between the radius and a straight line subtending the concave side of the blade.

One of the important features hereof is the employment of a suction fan, such as just described, arranged for causing efficient axial progress of the air and pulverized material, yet involving low consumption of power notwithstanding the excessively high speed of the shaft to which the fan is directly attached. A fan of ordinary design, or of full diameter, would be disadvantageous or even fatal to the proper action of the present machine, with its excessive rotary speed, and necessarily high suction or pressure. A very low pressure fan or blower is an important feature, in combination with means to cause the high pressure whirling matters to be diverted to the contracted outlet, because thus the maximum interior centrifugal pressure, and hence high pulverizing action, are maintained, where an excessive suction force would detract from the best conditions.

In the present machine the pressure and suction produced by the fan, and the power consumed, are maintained at a low point, by two features. The first of these is the substantial reduction of the diameter of the fan as compared with fans usually employed in pulverizing machines of the type referred to. The fan herein shown is characterized as having an outside diameter of its rotary parts substantially not more than about three quarters of the outside or tip diameter of the

rotary reducing means or beaters, or of the drum interior diameter. The result is a fan giving adequately effective action but reduced power consumption. The increase of pulverizing action due to the excessive speed of the shaft is not desired to be accompanied or impaired by a proportionate increase of suction and axial progress and rate of delivery.

The second mode of reducing the degree of suction and power consumption of the fan is by the tipping back of the fan blades, as described, namely, to an angle preferably well between 25° and 75° from the radius, as sufficiently illustrated in Figs. 2 and 4. A fan so constructed is adequately effective in action. The air and materials delivered to the interior of the fan are thrown or maintained in high speed whirling action, and the mixture is delivered tangentially through the fan casing exit 35. The high speed of rotation usually causes a severe centrifugal strain upon the parts. The direction in which the blades are tilted, as seen in Fig. 2, causes air pressure upon the blades toward the center, with a tendency to oppose the centrifugal force. Due to the stout structure of the parts of the fan, and their rigid interconnection, preferably by rivets, the fan hereof is extremely durable. At the same time it is capable of effectively driving the air and materials around within the fan casing and out through the tangential discharge.

Reference will now be made to the modifications of Figs. 5 and 6; that of Figs. 7 and 8 to be left to a later point as describing an extensively different embodiment from Figs. 1 to 6. Fig. 5 may be considered as showing a right hand elevation, partly in transverse section of certain parts. The left side shows a modified form of whirl obstructing blades 67, which instead of being radial as are the blades 65 in Fig. 1, are curved or concaved toward the direction of rotation of the reducing elements, indicated by the arrow. In Fig. 6 this curvature is increased to such an extent that each of the whirl obstructing blades 68 is substantially of spiral form. In either case the tendency of the materials being rapidly whirled near the periphery is to be thrown toward the center upon striking the blades. The radial blades of Fig. 1 will give this result to an effective extent, and the forms of Figs. 5 and 6 to an increased extent, thus assisting the drawing inwardly of the whirling matters, as is necessary to enable their delivery through the contracted aperture 30 into the fan. While the modified structures of Figs. 5 and 6 are thus particularly adaptable for use immediately preceding the fan chamber, they may be used also to replace the blades 60 between the two pulverizing chambers. Fig. 5 also indicates one of a

number of possible modifications of the pulverizing elements in each chamber, the disk 57 being of larger diameter than the disk 55 shown in Fig. 1, and the beating elements 58 being shown as of smaller size and fixed against pivotal movement.

The operation of the apparatus so far described may be substantially as follows. Crushed coal or other material is introduced into the hopper 37 at a measured rate, in accordance with the desired rate of consumption, the proportion of air to be suitably regulated in accordance therewith. The air inflow through the hopper and through the passage 22 carries the fuel through the central aperture 20 in the head 19 and thus into the first pulverizing chamber 51. Pieces of metal which are not separated out in the hopper and discharged by passage 22 will be thrown by centrifugal force from the first chamber through the lining aperture 18 into the discharge receptacle 15, and so removed. Within the first chamber the entering fuel is acted upon by the pulverizing means, in this case being struck by the paddles, and so initially reduced, and the reduced materials and air within the chamber are maintained in a very high state of rotation, and hence under a centrifugal pressure which keeps them near to the casing lining. Progressive attrition continues as the particles of material are acted upon by the paddles, the action depending not merely upon delivered blows but also upon a surface rubbing action, under pressure. The reducing action is also progressive in an axial direction as the axial flow causes gradual advancing travel of the whirling matters.

As already stated one of the features hereof is excessively high speed or rotation, not heretofore attained. The practical speed can not conveniently be stated in terms of angular motion, inasmuch as pulverizing machines are made of varying sizes, with proportionately lower rotary speeds in the larger sizes. With this invention, however, existing speed may be increased from 25% to 100%, for example a former peripheral speed of 225 feet per second can be increased to 280 feet per second or more, and even as high as 400 feet per second, or more, such speeds being prohibitive with heretofore known pulverizers. As an example a pulverizer with 24" paddle diameter, formerly operated at about 1100 to 1800 R. P. M. has been with this invention speeded up to 2500 R. P. M. or more, and even to 3600 R. P. M. The higher speed gives in itself an increased pulverizing action, and produces also a greatly increased centrifugal force, resulting in excessive centrifugal pressure through the pulverizing chambers. It is well known that centrifugal force increases as the square of the rotary speed, so that double speed

would involve quadruple centrifugal force. Due to this extreme centrifugal force, minute particles which heretofore have merely been carried around suspended in the air, can be thrown outwardly by centrifugal force, and thus caused to strike the lining of the casing, and to travel along in contact with it, greatly increasing the abrading and reducing action. The material speed increase therefore results in greater pulverizing action, not only between the particles of fuel and the paddles, but between the fuel and the casing. Thus is made apparent the advantage of the greatly increased speeds of rotation made available by this invention. Much finer and more uniform pulverization is attainable. Not only are better pulverization and greater output attained with the present invention, but increased life, as the wearing away of the paddles is reduced, the wear being substantially transferred to the casing lining, a cheap and easily replaced element.

The whirling materials in passing from the first to the second pulverizing chamber are compelled to pass between the fixed whirl obstructing vanes 60. These vanes are arranged to permit unimpeded axial flow, while abruptly stopping the whirling action. These elements not merely cause a very effective additional pulverizing action, due to the impact of the particles upon the vanes, and the attrition as the particles travel along the vanes, but also to a process of exclusion, by which the relatively heavier particles are caught up in eddies and thrown back into the first pulverizing chamber, as more fully described in my said prior patent. An additional resulting action is that due to the entry of the axially traveling materials into the second pulverizing chamber, wherein they are suddenly thrown from a zero speed of rotation to the full speed of the reducing elements or paddles in the second chamber. The pulverizing action in the second chamber is analogous to that in the first, the pulverizing action continuing progressively.

The high centrifugal pressure in the air and materials being reduced is maintained throughout the entire travel through the two reducing chambers. This is due to the absence of diaphragms or restricted passages between the chambers. There is no element substantially impeding the axial progress along the periphery from the inlet 20 to the outlet 30; thus differing from prior structures, in which annular diaphragms impair the peripheral pressure, and the high suction fan further reduces it. At the outlet 30 herein, however, is the diaphragm or head 29 with the restricted opening 30 into the fan chamber, and this presents a substantial problem in the necessity of drawing inwardly the fast whirling materials held forcibly outward by the extreme centrifugal pressure, and without impairing the action. Accord-

ing to this invention the desired result is secured by utilizing the large dynamic energy existing in the whirling materials, and by so applying it as to cause the materials to move inwardly as they progress axially, so that on reaching the head 29 the materials will be able to pass easily to and through the aperture 30 into the central part of the fan chamber. One mode of bringing the materials to the outlet is by the use of the whirl obstructing blades 65 placed between the final pulverizing chamber and the restricted outlet aperture 30. The combination of the high speed pulverizing elements, the relatively small aperture at the outlet end, and the whirl obstructing blades or equivalent between, gives the desired result, since the highly energized whirling matters as they advance axially into the spaces between the blades 65 are caused thereby to spread inwardly along the spaces between the blades, the whirling energy of the materials being converted into centripetal motion, so that the products passing progressively from the final pulverizing chamber are readily caused to draw inwardly and to pass through the contracted opening 30 into engagement with the fan.

Thus the described apparatus accomplishes the main object of the invention, permitting excessively high speeds of rotation without impairing the proper coordination and operation of the parts, including the necessary progress of the air and pulverized materials from the reducing chambers into the fan chamber. The principle of utilizing the dynamic energy of the whirling matters to bring them inward from the periphery to the necessary discharge point may be embodied in various ways. Thus Fig. 5 shows curved blades 67 between the final pulverizing chamber and the aperture leading to the fan; while Fig. 6 shows spiral blades, which not merely deflect but actually can inwardly the whirling materials so that they are readily dischargeable through the aperture 30. Figs. 7 and 8, as will later be described, show a yet different means, not embodying whirl restricting elements, for causing the dynamic energy of the whirling materials to bring the same inwardly sufficiently for discharge into the interior of the fan.

An end wall, such as 29 or equivalent, with its contracted aperture 30 between the final pulverizing chamber and the fan chamber, is an essential to the proper working of the high speed machine. The wall acts like a dam by which the high pressure peripherally whirling materials are confined. Without any restriction at this point the materials would progress rapidly from the casing and be discharged, making high centrifugal pressure impossible. I find that in order to obtain the finest degree of pulveri-

zation high internal pressure should be maintained along the entire length of the reducing chambers. The casing wall is seen to be cylindrical and at each end is an apertured wall, confining the materials peripherally, so that the high centrifugal pressure may be substantially uniform from end to end. This condition, and the need of the barrier or wall 29, creates the difficulty of securing the passage of the materials from their peripheral position into the fan chamber, which difficulty, as already explained, is overcome by the vanes or blades 65, serving as a diverting means, and allowing easy transition from the high pressure conditions within the pulverizing chambers to the low pressure conditions in the fan chamber. Such low pressure conditions in the fan chamber are of great practical desirability and enable the employment of a fan having small power consumption. The structure of the fan, and its small diameter, have already been referred to. This cooperates with the small diameter opening 30 between the fan chamber and the main casing, since the materials passing through the opening will thereby be delivered into the interior of the fan and thrown into high speed rotation, and thus delivered tangentially from the fan casing into the pipes leading to a furnace, a place of storage, or the like. The fan, owing to its small diameter and the described tilt of its blades, will effectively rotate and tangentially deliver the air and pulverized fuel, and this with minimum consumption of power, notwithstanding the high rotary speed of the shaft carrying the fan.

Figs. 7 and 8 show a modified pulverizer structure embodying the same underlying principles as the structure described. The base 100 supports a casing 101, having a first end wall or head 102 formed with a central aperture 103, through which fuel or other material is passed into the pulverizer from an exterior hopper 104. An extension 105 gives support to a bearing 106, in which runs shaft 107 having at its further end a second bearing 108, mounted on a standard 109. The shaft is shown as provided with a driving gear 110 by which it may be maintained in the desired high speed rotation.

At its interior side the casing or drum 101 is lined with a cylindrical lining 111 which cooperates with the reducing elements in the reduction of the material. On the shaft 107 is shown a hub 112 carrying a series of disks 113 upon which are mounted a number of swinging beaters 114 supported by a pivot shaft 115.

The far end of the casing is formed with a second head or end wall 116 having a discharge aperture 117 small enough to deliver materials into the interior of the fan to be described. As a means of utilizing the dy-

dynamic energy in the whirling materials to cause them to draw inwardly after traveling axially beyond the pulverizing chamber is shown a modified arrangement, different from that of Figs. 1, 5 and 6, and consisting of a tapered or conical wall 118 extending from the casing cylindrical wall 101, adjacent to the pulverizing elements, at an inward slant to a point on the end wall 116, substantially adjacent to the central opening 117; and this conical wall 118 may have a lining 119. By this arrangement the fast whirling materials, with high inertia, as the suction from the fan chamber draws them onwardly, are caused gradually to assume whirling paths of less and less diameter, until finally they may readily pass through the aperture 117 into the fan chamber.

The fan chamber is enclosed by a casing 120 generally circular, but having a tangential discharge opening 121. The fan comprises a hub 122 mounted on the driving shaft, with a series of spokes 123 giving support to annular rings 124 which in turn give support to fan blades 125 which may consist of transverse plates tilted in the manner already described. The fan chamber is shown as formed also with an auxiliary air inlet 126, which may be damper controlled. It will be noted that, as in the previous embodiment, the fan diameter is much less than the beater diameter. In each case the fan diameter is not more than three fourths of the beater diameter, a feature of combination possessing material importance; in the illustration of the fan diameter is shown about two thirds of the beater diameter.

The features shown in Figs. 7 and 8 which are not illustrated in the main figures are not made the subject of claim herein, but are claimed in a copending application Serial No. 199,528 filed June 17, 1927.

The modification shown in Fig. 9 differs in several respects from that of Figs. 7 and 8. A different type of beaters is shown, Hubs 112^a, on the shaft 107, carry disks or webs 113^a with paddles 114^a at their ends, more analogous to those shown in Fig. 1. Two sets of such beaters are shown, spaced from each other, permitting whirl obstructing vanes 60^a to be inserted between them, analogous to the vanes 60 in Fig. 1. The conical outlet 118 may also be modified as seen in Fig. 9, by the provisions of fixed vanes 65^a, serving not only to obstruct rotation and increase pulverization, but also assisting the inward diversion of the whirling matters to bring them to the outlet aperture 117.

Fig. 10 shows a modification available for use in an embodiment such as that in Fig. 7. In this modification the conical outlet portion 118 of the casing, or at least the lining member 119 thereof is shown provided with

helical-spiral ribs 130. These are of moderate height and so inclined that the whirling action of the materials, upon engagement with the ribs tends to promote their advance inwardly along the conical wall to the contracted outlet 117. The ribs form grooves 131 between them, and the whirling materials upon reaching these grooves are automatically carried inward and forward toward the discharge. In this way the dynamic energy of the whirling materials is utilized to bring them inwardly as stated at the outset. By proper designing this action can be increased to such an extent as to give a driving or blowing action, not merely dispensing with a high pressure fan, but in some cases wholly dispensing with the need of an exterior fan or blower, which remark applies also to the form shown in Fig. 6.

The operation may be described as consisting of driving air and the material whirling within a chamber at excessive speed, while confining it against peripheral egress during pulverization, namely by the head or heads with contracted apertures, and utilizing the dynamic energy of the whirling matters for causing them to divert inwardly to the contracted outlet, whereby progressive advance of the material being pulverized may be maintained. Preferably the whirling motion referred to is produced by pulverizing means of the impact beater type, rotated at high speed and producing high centrifugal pressure along the chamber, while the deflecting of the matters toward the axis is effected by a special interior element or formation located between the beating devices and the contracted outlet, whereby low pressure suction means may be sufficient to draw the matters progressively from the chamber, and without impairing the high interior centrifugal pressure.

The invention may be described as comprising a chambered casing with an operating shaft therein, suitable pulverizing means rotated by the shaft and causing rapid whirling of the air and material being pulverized, the casing having a head with contracted outlet aperture, and means for diverting the whirling matters from a peripheral point inwardly to said outlet aperture, so that progress of the whirling matters through the casing may be maintained. More specific features are the preferably cylindrical form of casing, with its contracted-apertured heads at both the inlet and outlet ends, and the pulverizing means consisting of impact beaters or paddles mounted on the shaft in an arrangement concentric with the casing. Unless the means deflecting the whirling matters to the outlet is sufficient to dispense with exterior suction means it is preferable to employ a low pressure fan arranged outside the outlet and operated by the same shaft that rotates the pulverizing means.

It will thus be seen that I have described a pulverizing machine embodying the principles and attaining the objects of the present invention; but as many matters of method, operation, structure, combination, arrangement and detail may be variously modified without departing from the principles of the invention it is not intended to limit the same to such matters except so far as set forth in the appended claims.

What is claimed is:

1. Apparatus for pulverizing fuel or other materials comprising the combination of means for driving air and material whirlingly within a chamber at excessive speed, walls enclosing such chamber and confining the material against peripheral egress at either end or between the ends of the chamber during pulverization, while presenting a contracted outlet, whereby high interior centrifugal pressure of the materials may be maintained during the progress of the whirling materials through the chamber, and means utilizing the dynamic energy of the whirling matters consisting of whirl obstructing surfaces arranged to cause the whirling matters to impact against such surfaces and to spread inwardly to said contracted outlet, whereby progressive advance and delivery of the material being pulverized may be maintained.

2. A pulverizing machine comprising a chambered casing free from peripheral egress openings and having contracted admission aperture at its inlet end, and contracted discharge opening at its outlet end, an operating shaft therein, pulverizing means rotated by said shaft and causing rapid whirling of the air and material being pulverized so as to produce high centrifugal pressure along the chamber periphery, the casing being interiorly substantially free from obstruction to axial progress of the whirling matters between the pulverizing means and contracted outlet, and interior blades adjacent the outlet and arranged to cause the whirling matters to be spread and diverted along said blades inwardly to said outlet aperture.

3. A pulverizing machine comprising a chambered casing having means for admitting fuel and air to its inlet end, an operating shaft therein, pulverizing means rotated by said shaft and causing rapid whirling of the air and material being pulverized so as to produce high centrifugal pressure along the chamber periphery, the casing formed with a contracted outlet aperture, and being interiorly substantially free from obstruction to axial progress of the whirling matters between the pulverizing means and contracted outlet, means for using the live energy of the whirling matters to assist their diversion from a peripheral point inwardly to said outlet aperture, and

suction means beyond the outlet aperture arranged to draw the whirling matters from the casing and comprising a low power rotary fan, with blades tilted back between 25° and 75° from the radius.

4. A pulverizing machine comprising a casing enclosing a substantially cylindrical chamber free of peripheral egress, a rotary shaft extending axially through such chamber, rotary impact beaters on said shaft within the casing and extending into proximity to the chamber peripheral wall, the casing having a head at each end, with a contracted inlet opening in one head and contracted outlet opening in the other head, both substantially smaller than the chamber diameter, and being interiorly free of substantial obstruction to axial progress of the whirling matters from the inlet to the contracted outlet, and impact means causing the whirling matters to be diverted inwardly to said outlet opening.

5. A pulverizer as in claim 4 and wherein is located beyond the outlet a low power suction fan mounted on the same shaft as that carrying the beaters, but of diameter not more than three-fourths of that of the beaters.

6. A pulverizing machine comprising a casing enclosing a substantially cylindrical chamber, a rotary shaft extending axially through such chamber, rotary impact beaters on said shaft within the casing and extending into proximity to the chamber peripheral wall, the casing having a head at each end, with a contracted inlet opening in one head and contracted outlet opening in the other head, both substantially smaller than the chamber diameter, and being interiorly free of substantial obstruction to axial progress of the whirling matters from the inlet to the contracted outlet, means causing the whirling matters to be diverted inwardly to said outlet opening; and a low power suction fan located beyond the outlet mounted on the same shaft as that carrying the beaters, and with concave blades tilted back from the radius.

7. A pulverizing machine comprising a casing having contracted inlet and outlet, pulverizing means rotatable in the casing to cause rapid whirling of the air and material to be pulverized, and impact means or blades in the casing adjacent the outlet causing the whirling matters by their whirling energy to divert inwardly to the outlet.

8. A pulverizing machine comprising a casing having a contracted outlet, pulverizing means rotatable in the casing to cause rapid whirling of the air and material to be pulverized, and impact means in the casing adjacent the outlet causing the whirling matters by their whirling energy to divert inwardly to the outlet, comprising a plurality of blades extending inwardly from the

periphery to the outlet whereby the whirling matters may spread inwardly on said blades to the outlet.

9. A pulverizing machine comprising a casing having a contracted outlet, pulverizing means rotatable in the casing to cause rapid whirling of the air and material to be pulverized, and impact means in the casing adjacent the outlet causing the whirling matters by their whirling energy to divert inwardly to the outlet, comprising a plurality of fixed blades extending, inwardly from the periphery to the outlet whereby the whirling matters may spread inwardly on said blades to the outlet.

10. A pulverizing machine comprising a casing having a contracted outlet, pulverizing means rotatable in the casing to cause rapid whirling of the air and material to be pulverized, and impact means in the casing adjacent the outlet causing the whirling matters by their whirling energy to divert inwardly to the outlet, comprising a plurality of curved blades extending inwardly from the periphery to the outlet whereby the whirling matters may spread inwardly on said blades to the outlet.

11. A high speed pulverizer comprising a chambered casing, an operating shaft therein, pulverizing means rotated by said shaft and causing rapid whirling of the air and material being pulverized, the casing having a head with contracted outlet aperture, and means for diverting the whirling matters from a peripheral point inwardly to said outlet aperture consisting of a series of blades extending substantially inwardly from the periphery and arranged to obstruct whirling motion without obstructing axial progress, whereby the whirling matters impacting on such blades are caused to spread inwardly and thus reach the outlet.

12. A high speed pulverizer comprising a chambered casing having means for admitting fuel and air to its inlet end, an operating shaft therein, pulverizing means rotated by said shaft and causing rapid whirling of the air and material being pulverized so as to produce high centrifugal pressure along the chamber periphery, the casing formed with a contracted outlet aperture, and being interiorly substantially free from axial obstruction to free outgoing progress of the whirling matters between the pulverizing means and contracted outlet, and means for using the live energy of the whirling matters to cause their diversion from a peripheral point inwardly to said outlet aperture, consisting of relatively stationary blades ex-

tending inwardly from the periphery of the axially-unobstructed space between the pulverizing means and outlet.

13. A high speed pulverizing machine comprising a casing enclosing a substantially cylindrical chamber having its peripheral portion substantially clear of obstruction to axial flow, a rotary shaft extending axially through such chamber, rotary impact beaters on said shaft within the casing and extending into proximity to the chamber peripheral wall, the casing having a contracted inlet opening at one end and contracted outlet opening at the other end, said outlet opening being substantially smaller than the chamber diameter, and means assisting the whirling matters inwardly to said outlet opening consisting of curved blades extending from the periphery substantially to the center and arranged to be impacted by the whirling matters and thus cause them to spread along the blades to an inward point, without substantial axial obstruction.

14. A high speed pulverizer comprising a chambered casing having means for admitting fuel and air to its inlet end, an operating shaft therein, pulverizing means rotated by said shaft and causing rapid whirling of the air and material being pulverized so as to produce high centrifugal pressure along the chamber periphery, the casing formed with a conical outlet portion and contracted aperture, and said conical portion containing blades arranged not to obstruct axial progress but to assist the spreading and diverting inwardly of the whirling matters.

15. A pulverizer as in claim 14 and wherein is a suction fan beyond the outlet aperture.

16. A high speed fuel pulverizing machine comprising a chambered casing substantially free from peripheral egress openings and from obstruction to axial progress of the whirling matters and having a contracted inlet aperture and means for admitting fuel thereto, an operating shaft in said casing, a first pulverizing device on said shaft near said inlet and causing rapid whirling of the air and material being pulverized, a set of whirl obstructing blades following said first pulverizing device, a second pulverizing device on said shaft between said blades and the outlet, and said casing formed with a tapered outlet end terminating in a contracted outlet.

In testimony whereof, I have affixed my signature hereto.

PAUL ARTHUR HIRSCH.
